UNITED STATES PATENT OFFICE.

THOMAS HARRISON SYMINGTON, OF BALTIMORE, MARYLAND, ASSIGNOR
TO THE T. H. SYMINGTON COMPANY, A CORPORATION OF DELA-
WARE.

CORE FOR MAKING HOLLOW CASTINGS.

SPECIFICATION forming part of Letters Patent No. 788,612, dated May 2, 1905.

Application filed December 7, 1903. Serial No. 184,111.

To all whom it may concern:

Be it known that I, THOMAS HARRISON SYMINGTON, a citizen of the United States of America, residing at Calvert Building, Baltimore city, Maryland, (and whose post-office address is Calvert Building, Baltimore city, Maryland,) have invented certain new and useful Improvements in Cores for Making Hollow Castings, of which the following is a specification.

My invention relates to a core used for casting, and is specially designed for the manufacture of a cheap and practical core for casting journal-boxes for railroad-cars.

In the casting of journal-boxes heretofore difficulty has been experienced in getting a green core to stand up during handling and casting. This may be accomplished by baking the whole core; but this is difficult and expensive. I have invented a core which is entirely practical and at the same time easy to handle, strong, and cheap to construct.

My invention consists of a core for casting journal-boxes the lower portion of which is of dry sand and is suspended from a suitable support, the upper portion of which is of green sand and is supported by the dry part, thus forming a strong and comparatively cheap core for a complicated casting.

In the drawings, Figure 1 is a vertical section of a core-box in which the dry core is made. Fig. 2 is a vertical section of the core-box in which the green core is made superimposed upon the dry core. Fig. 3 is a plan of the completed core. Fig. 4 is a side elevation of the completed core. Fig. 5 is a vertical longitudinal section of the mold with the core in full elevation and showing the casting in section.

Referring to Fig. 1 of the drawings, 1 is a core-box in which is molded a sand core 2, and when made a staple 3 is embedded in it.

This core 2 when molded is removed from its core-box and baked in an oven, so as to give it the desired degree of hardness and strength so that it may be suspended from a rod 5 when placed in the green-sand-core box and in the mold and also so that it may safely sustain the weight of the green-sand core which is built up upon it.

Referring to Fig. 2 of the drawings, 4 is the green-sand-core box, in the lower part of which the dry-sand core 2 is suspended from the rod 5, which passes through the core-box and the two ends of which rest in the openings in either end of the core-box. 6 is a dry-sand core made in another core-box and baked and set up in a suitable groove in the core-box, so as to be incorporated into the core. The vacant part of the core-box is then packed with green sand occupying the space marked 7 in Figs. 2, 3, 4, and 5, and the core is complete, as shown in Figs. 3 and 4. The core is then removed from the core-box and placed in the mold 8, as shown in Fig. 5, and a box cast within the mold and around the core, as shown in Fig. 5 at 9.

Having thus described my invention, what I claim, and desire to secure by Letters Patent, is—

A core for casting composed of a section of baked sand, a hanger embedded in said baked portion, a support co-operating with the hanger to support the baked section and a section composed of green sand superimposed upon the baked sand.

Signed by me at Baltimore city, Maryland, this 9th day of November, 1903.

THOMAS HARRISON SYMINGTON.
